UNITED STATES PATENT OFFICE.

JOHN WRIGHT SEAVER, OF CLEVELAND, OHIO, ASSIGNOR, BY MESNE ASSIGNMENTS, TO THE WELLMAN-SEAVER-MORGAN COMPANY, OF CLEVELAND, OHIO, A CORPORATION OF OHIO.

SHIP-BUILDING PLANT.

SPECIFICATION forming part of Letters Patent No. 747,782, dated December 22, 1903.

Application filed October 28, 1901. Serial No. 80,266. (No model.)

To all whom it may concern:

Be it known that I, JOHN WRIGHT SEAVER, a citizen of the United States, and a resident of Cleveland, Ohio, have invented certain Improvements in Ship-Building Plants, of which the following is a specification.

The object of my invention is to so construct a ship-building plant as to effectively utilize all of the available ground area and to reduce to a minimum the labor of handling the plates, beams, and other elements of the ship. This object I attain by extending the roof-trusses of a shop structure so as to cover the ship-building way or ways and providing these projecting portions of the trusses with cranes for handling the material used in the construction of the ship.

In the accompanying drawings, Figure 1 is a transverse section of a ship-building plant constructed in accordance with my invention, and Fig. 2 is a similar view illustrating another method of carrying out my invention.

The structure shown in Fig. 1 comprises opposite longitudinal rows of vertical beams or columns having the spaces between the same suitably filled in, so as to constitute the opposite walls 1 of a shop which has roof-trusses 2, projecting on each side beyond the sides of the roof, as shown at 3, so as to form trusses for the support of cranes 4, there being in the present instance two cranes disposed end to end on each of the projecting trusses 3, although but a single crane can be carried by each of said trusses, if desired.

The central inclosed portion of the structure constitutes a shop which may contain punching, shearing, and other machinery—such, for instance, as shown at 5—and which may, if desired, have a floor 6, so as to divide it into upper and lower stories 7 and 9, the lower story receiving the heavy machinery which requires a firm foundation and the upper story being used for storage purposes or for the reception of light machinery, such as 45 woodworking-tools and the like.

When the central structure has considerable span, a central row of columns 10 may be employed to support the floor 6, as shown in Fig. 1, and also to support the inner running ways of cranes 11, with which the shop is

provided, a single crane being used when the central row of columns is not employed.

The walls 1 have suitable windows 12 for properly lighting the shops, and for the same purpose the roof has a central skylight 13, 55 and the floor 6 has a central skylight 14, and at desired intervals the walls 1 may be provided with openings normally closed by sliding doors 15, so that material can be removed from the shop at the most convenient point. 60

On each side of the shop in the spaces overhung by the projecting roof-trusses 3 are the ship-building ways, the columns constituting part of the walls of the shop being, if desired, utilized for the support of gangways 65 or scaffolding 16.

In that form of my invention illustrated in Fig. 2 the intermediate floor 6 is dispensed with, the shop having but a single story and a single crane 17 being employed instead of 70 the two cranes 11, as shown in Fig. 1.

In a ship-building plant constructed in accordance with my invention all of the ground area is effectively utilized, and the machines whereby plates and other parts of the ship structure are prepared for use bear such relation to the ship-building ways that the parts can be handled with a minimum expenditure of time and labor, and consequently at the least expense, the trusses 2 serving the double 80 purpose of roof-trusses for the shop and supports for the cranes which serve the ways. Hence the structure is most economical, since the use of a central supporting structure for the crane-trusses is necessary in any case, 85 and by my invention the erection of a separate shop for the punching, shearing, and other preparatory machinery is rendered unnecessary.

If desired, the roof-trusses may project beyond the shop on one side only, so as to serve but a single ship-building way, but the construction shown is of course preferred.

Having thus described my invention, I claim and desire to secure by Letters Patent—

1. A ship-building plant comprising an inclosed structure having walls and a roof provided with a series of roof-trusses, each of said trusses having an extended portion pro-

jecting beyond said inclosure, tracks supported by the projecting portions of the trusses and extending at right angles to the planes of said trusses, and a crane constructed to operate on said tracks, substantially as described.

2. The combination in a ship-building plant, of an inclosed structure having a series of trusses for supporting the roof thereof, each of said trusses having portions extending on both sides of the inclosed structure, tracks supported by the projecting portions of the truss, other tracks supported on the outside of the wall-supporting framework of the inclosed structure and cranes constructed to operate upon the tracks, said tracks extending at right angles to the planes of the trusses, substantially as described.

3. The combination in a ship-building plant, of an inclosed structure having walls and a roof, with a series of substantially parallel

trusses for supporting said roof, said trusses having portions extending outside of the inclosed structure, three tracks supported from the under side of said extended portions of the trusses, one of the same being adjacent to the outer ends thereof and the others being carried at substantially the middle portions of said trusses, with a track supported on the outside of the wall-supporting framework of the inclosed structure, and cranes operative upon said tracks and movable in lines at right angles to the planes of the trusses, substantially as described.

In testimony whereof I have signed my name to this specification in the presence of two subscribing witnesses.

JOHN WRIGHT SEAVER.
